CASTER BRACKET FOR CANS

Dominick Coviello, Newark, N. J.

Application September 30, 1949, Serial No. 118,821

4 Claims. (Cl. 16—30)

1

This invention relates to an improved caster bracket utilizing a conventional or standard caster roller, and especially, but not exclusively for attachment to the bottom rim flanges of ash cans, garbage cans, oil drums and the like, to render the same easily and noiselessly rollable over the ground or other surface upon which they are usually dragged or rolled upon their bottom flanges.

The primary object of the invention is to provide caster roller brackets of the character indicated above which are capable of being easily and quickly installed without special skill in a secure and mechanically-efficient manner to the bottom flange of such as an ash can, and of being quickly and easily removed therefrom, without tools other than a screw driver.

Another important object of the invention is the provision of caster roller brackets of the above-indicated character which are of simple and rugged construction, involving a minimum number of parts, and can be made in a serviceable and attractive form at relatively low cost.

Other important objects and advantageous features of the invention will be apparent from the following description and the accompanying drawings, wherein, for purposes of illustration only, a specific embodiment of the invention is set forth in detail.

In the drawings:

Figure 1 is a bottom perspective view of an ash can equipped in accordance with the present invention;

Figure 2 is an enlarged fragmentary vertical transverse section taken on the line 2—2 of Figure 3;

Figure 3 is a top plan view of a caster roller bracket;

Figure 4 is an outboard elevation thereof.

Referring in detail to the drawings, the illustrated caster roller brackets 5 are shown installed on the bottom rim flange 6 of an ash can 7, a minimum of three brackets being required for rollably supporting the ash can in stable or set position on a supporting surface 8.

Each bracket 5 comprises a preferably one-piece body consisting of a horizontally-elongated, generally-rectangular and plane face plate 9 having inwardly-turned ends 10, a bight portion 11 of reduced width fixed to project inwardly from the lower edge of the face plate 9, and a similarly narrow, vertical arm 12 fixed to rise from the rear edge of the bight portion 11 to a point less than half the height of the face plate 9.

The face plate 9 has punched outwardly there-

2

from a series of similar horizontally-elongated keepers 14 arranged in vertically-spaced alignment along the vertical center of the face plate 9 from top to bottom thereof. Four of the keepers 14 are shown, and they, in conjunction with the outboard surface of the face plate 9, form a journal for the spindle 15 of a standard caster roller 16. The caster roller 16 involves an annular shoulder 17 at the lower end of the spindle 15, upon which the lower end or edge of the bracket body rests, as shown in Figures 2 and 4, this shoulder enclosing bearing means (not shown) on the upper end of a laterally-offset fork 18 in which the roller wheel 19 is journaled. The upper end of the spindle 15 has a cylindrical enlargement or head 15' and the lower end thereof of a similar enlargement 16' which enlargements fit snugly between the outboard surface of the face plate 9 and the upper and lower keepers 14, whereby the spindle is journaled on the outboard side of the face plate 9.

A horizontal spring arm 22 secured at one end to the face plate 9 at one side of the series of keepers 14 extends across the series of keepers with its free end 23 at the far side thereof, the intermediate portion of the spring arm 22 being tensioned against the caster roller spindle 15 beneath the upper enlargement or head 15', whereby the spindle is releasably held in place with the shoulder 17 engaged with the under side of the bracket body.

It will be observed that in the event the action of the caster roller wheels 19 is not desired, the caster rollers are easily removable by pulling them downwardly so as to displace the spring arm 22 and pass the spindle head 15' below the spring arm 22, whereupon the bracket bodies can act as feet for slightly spacing the bottom flange 6 from the ground.

For removably securing a bracket 5 on the can bottom flange 6, the ends of the face plate 9 are traversed by adjusting screws 20, 20 positioned in horizontal alignment with a thumb screw 21 traversing the vertical arm 12. The device is simply slipped over the can rim flange 6 and the thumb screw 21 tentatively tightened against the inboard side of the flange 6 so as to engage the middle of the face plate 9 with the outboard side of the flange 6. The adjusting screws 20 are then adjusted, if necessary, to position the face plate tangentially with respect to the rim flange 6 and equally spaced therefrom at the ends 10, whereupon the thumb

55

screw 21 is tightened to lock the device in place.

What is claimed is:

1. A caster roller bracket for installation on the bottom rim flange of a container, comprising a body comprising a vertical face plate to engage the outboard side of the rim flange, a horizontal portion projecting inwardly therefrom, a vertical arm on the rear end of said horizontal portion to rise along the inboard side of the rim flange, a screw traversing said vertical arm to engage the inboard side of the rim flange and force said face plate against the outboard side of the rim flange, journal means on said face plate, and a caster having a spindle journaled in said journal means and a rest engaging the lower of said body, and a swiveled wheel below said rest, said journal means comprising upper and lower keepers projecting on the outboard side of said face plate with said caster spindle confined between said keepers and the outboard side of said face plate.

2. A caster roller bracket for installation on the bottom rim flange of a container, comprising a body comprising a vertical face plate to engage the outboard side of the rim flange, a horizontal portion projecting inwardly therefrom, a vertical arm on the rear end of said horizontal portion to rise along the inboard side of the rim flange, a screw traversing said vertical arm to engage the inboard side of the rim flange and force said face plate against the outboard side of the rim flange, journal means on said face plate, and a caster having a spindle journaled in said journal means and a rest engaging the lower end of said body, and a swiveled wheel below said rest, said journal means comprising upper and lower keepers projecting on the outboard side of said face plate with said caster spindle confined between said keepers and the outboard side of said face plate.

3. A caster roller bracket for installation on the bottom rim flange of a container, comprising a body comprising a vertical face plate to engage the outboard side of the rim flange, a horizontal portion projecting inwardly therefrom, a vertical arm on the rear end of said horizontal portion to rise along the inboard side

of the rim flange, a screw traversing said vertical arm to engage the inboard side of the rim flange and force said face plate against the outboard side of the rim flange, journal means on said face plate, and a caster having a spindle journaled in said journal means and a rest engaging the lower end of said body, and a swiveled wheel below said rest, said journal means comprising upper and lower keepers projecting on the outboard side of said face plate with said caster spindle confined between said keepers and the outboard side of said face plate, said keepers being integral with the face plate.

4. A caster roller bracket for installation on the bottom rim flange of a container, comprising a body comprising a vertical face plate to engage the outboard side of the rim flange, a horizontal portion projecting inwardly therefrom, a vertical arm on the rear end of said horizontal portion to rise along the inboard side of the rim flange, a screw traversing said vertical arm to engage the inboard side of the rim flange and force said face plate against the outboard side of the rim flange, journal means on said face plate, and a caster having a spindle journaled in said journal means and a rest engaging the lower end of said body, and a swiveled wheel below said rest, said journal means comprising upper and lower keepers projecting on the outboard side of said face plate with said caster spindle confined between said keepers and the outboard side of said face plate, said keepers being integral with the face plate, and punched-out of the face plate in the form of horizontally-elongated strips attached at both ends to the face plate.
